TEXAS.

PEAR-BURNER.

1,074,374.

Specification of Letters Patent. Patented Sept. 30, 1913.

Application filed November 5, 1912. Serial No. 729,583.

To all whom it may concern:

Be it known that we, JOHN J. MESERLI and JESSE L. MAYFIELD, citizens of the United States, and residents, respectively, 5 of Kingsville, in the county of Nueces and State of Texas, and Corpus Christi, in the county of Nueces and State of Texas, have invented certain new and useful Improvements in Pear-Burners, of which the following is a specification.

Our invention relates to burners of the type suitable for use with hydrocarbon fuels and adapted to be manipulated directly by hand, being used for instance for 15 burning small objects located in positions not readily accessible.

More particularly stated, our invention comprehends a burner of this general character and having such form as to adapt it specifically for burning off the pines of cactus, 20 prickly pears, and the like.

It is a fact that many tropical and semi-tropical plants more or less related to the cactus family can be used for food for cattle, provided the spines or needle-like projections with which such vegetation is usually covered can be effectively removed. This is most readily done by applying to the 25 leaves of the vegetation a flame from a burner carried in the hand of the operator. In order to render a burner of this kind effective, it should be capable of vaporizing the hydrocarbon fuel employed, and in doing this the vapor should be heated by the flame 30 of the burner. During the step of heating, however, the liquid hydrocarbon should be so supplied to the burner that the heat of the latter in causing vaporization does not set up undue back pressure in the supply 35 pipe through which the fuel is fed to the burner. Care should also be exercised to insure a gradual and uniform vaporization of the liquid rather than violent ebullition of the same.

40 In our device we seek to feed the hydrocarbon liquid into a heating coil carried by and forming a part of the burner, the introduction of the liquid into this coil being effected at the coolest part of the coil, 45 so that as the liquid wends its way through the various loops or convolutions of the coil, the liquid gradually becomes heated and after this readily makes its escape by continuing its initial direction of movement. 50 We further seek to provide an improved de-

vice of this character in which the hydrocarbon fuel employed is lodged in a compartment adjacent to the upper end of a handle in order to be readily supplied from said compartment to facilitate the burning 60 of objects located overhead relatively to the operator who is manipulating the handle. We also seek to provide an improved construction of air pump for forcing air into the handle from which the hydrocarbon 65 liquid is supplied.

Reference is made to the accompanying drawing forming a part of this specification and in which like letters indicate like parts.

70 Figure 1 is a side elevation showing our improved burner complete and ready for use; Fig. 2 is a detail showing in fragmentary section the burner mechanism; Fig. 3 is a detail showing in section the heating 75 coil used for vaporizing the hydrocarbon liquid fuel; and, Fig. 4 is a detail showing the burner head carrying the burner tip. Fig. 5 is a fragmentary section through the tank showing the parts contained thereby.

75 A tank 4 having the form of a longitudinal cylinder serves the double purpose of a handle and fuel tank. The cylinder 4 is provided at its ends with caps 5, 6. An air pump barrel 7 is mounted upon the 80 cap 6, and forms part of the air pump for the purpose of producing an air pressure within the cylinder. The cap 6 is closed by a plug 8 which is removed from time to time to permit the introduction of hydro- 85 carbon liquid in the cylinder.

90 Extending from the cap 6 is a pipe section 9 which carries a hand valve 10. A pipe section 11 is connected to the pipe section 9 by a flexible pipe joint 12. Another pipe 95 section 13 of smaller diameter than the pipe section 11 is connected with the latter by aid of a reducing thimble 14. A hood 15 having generally the form of a cylinder open at its ends is mounted upon the pipe section 13.

95 Connected with the pipe section 13 and preferably integral with the same is a heating coil 16. Extending through this heating coil is a portion 16^a of straight pipe, 100 and mounted upon the outer or free end of this portion is a burner head 17. Located within one end of the tank 4 is a partition 20 so arranged as to form a compartment 21. The pipe section 9^a extends from the 105 110

cap 6 and into this compartment, being held in position by aid of a boss 22. The burner head 17 may, if desired, be an ordinary pipe section and the burner tip 18 may 5 be of any approved construction but in this instance is made massive in form in order to enable it to withstand heat. The burner head 17 may be threaded internally at 19 and screwed on the pipe section 16^a, but 10 the precise manner of its attachment is immaterial. The inner end of the pump cylinder 7 is secured to an angle block 23 the latter being provided with an L-shaped passage 24 which merges into a recess 25. 15 A valve casing 26 having a cylindrical form is secured to the tank 4 and extends radially inward therefrom being secured at its inner end to the angle block 23. A nipple is shown at 27 and extending inwardly 20 from this nipple is a valve rod 28 carrying a number of valve cups 29 made in this instance of leather. The valve casing 26 is provided with two small holes 30 through which air is forced into the tank 4. A 25 pump rod is shown at 31 and carries a cup valve 32 and a handle 33. When the pump rod 31 is reciprocated by aid of the handle 33, air is forced into the tank 4 and compressed. If now the tank contains a 30 supply of liquid hydrocarbon fuel and a portion of this fuel is within the compartment 21 and air is pumped into the tank as above described, the air pressure tends to expel the hydrocarbon fuel through the pipe sections 9, 11, 13, the heating coil 16 and burner tip 18.

The operation of our device is as follows:—The parts being assembled as above described and a quantity of liquid hydrocarbon fuel having been placed in the tank, the pump handle is operated as above described, and heat being applied to the heating coil 16 so as to vaporize the hydrocarbon, the vapor is lighted and a flame 45 therefore issues from the hood 15. The operator now uses the cylindrical tank 4 as a handle and by its aid may direct a flame against objects to be burned. Even when the objects are located overhead, the 50 operator has no difficulty in applying the flame to them, because when the tank 4 is used as a handle and its end nearest the hood 15 is raised to a considerable angle upward, the fuel within the compartment 55 21 is readily forced through the pipe as above described. The burner as a whole may therefore be inclined either downwardly or upwardly as desired.

The device is of special service in burning off the thorns and needles growing upon various plants of the cactus kind and may

be easily manipulated so that the burner flame is thrown against portions of the plant which are otherwise not readily accessible.

It will be noted that when the hydrocarbon fuel is fed into the heating coil 16 it first reaches the coolest portion of the coil. As the liquid follows the interior of the heating coil, it comes into contact with 70 successively hotter and hotter and hotter portions of the coil. The liquid is thus vaporized and by the time it gets entirely through the coil it is completely formed into vapor. Except for the provision of 75 feeding the hydrocarbon fuel into the coolest part of the coil and gradually conducting it into successively hotter portions, it is possible that violent ebullition might take place owing to the sudden conversion 80 of the hydrocarbon fuel into vapor. By our arrangement, the vapor thus formed can produce no sudden or excessive back pressure and no violent ebullition can be so produced as to endanger the safety of 85 the apparatus.

We do not limit ourselves to the exact construction shown, as variations may be made in the form of our invention without departing from the spirit thereof.

Having thus described our invention, we claim as new and desire to secure by Letters Patent.

A pear burner comprising a tank having a substantially tubular form and adapted 95 to hold a hydrocarbon liquid, a valve casing containing valve mechanism and extending radially into said tank, a pump barrel extending axially into said tank, an angle block mounted upon said valve casing and connected with said pump barrel for the purpose of supporting the latter within said tank, said angle block having a passage extending through it for the purpose of establishing communication 100 between said valve casing and said pump barrel, a partition disposed across said casing and provided with a bottom so as to form a compartment for holding a quantity of liquid hydrocarbon, a pipe extending 105 into said casing and into said compartment, and a burner carried by said pipe.
